UNITED STATES PATENT OFFICE

FÉLICIE EUGÉNIE AMÉLIE WANPOUILLE BERGAUD, OF PARIS, FRANCE

DESIGN FOR A BOX

Application filed August 13, 1932. Serial No. 44,594. Term of patent 14 years.

To all whom it may concern:

Be it known that I, FÉLICIE EUGÉNIE AMÉLIE WANPOUILLE BERGAUD, a citizen of the French Republic, residing at 43 Boulevard Suchet, Paris, France, have invented a new, original, and ornamental Design for Box, of which the following is a specification, reference being had to the accompanying drawing, forming part thereof.

Fig. 1 is a bottom view of a box, showing my new design;

Fig. 2 is a side elevation thereof;

Fig. 3 is a front elevation thereof;

Fig. 4 is a top plan view thereof.

I claim:

The ornamental design for a box, as shown.

Dated, August 5, 1932.

FÉLICIE EUGÉNIE AMÉLIE WANPOUILLE BERGAUD.
